By Mark Clark Atlys.

UNITED STATES PATENT OFFICE.

HENRI COLOMB, OF TAVANNES, SWITZERLAND.

JEWEL SETTING FOR WATCHES AND METHOD OF MAKING SAME.

Application filed March 26, 1925, Serial No. 18,560, and in Switzerland July 18, 1924.

Heretofore jewels were fixed inside of the settings used in watch making by the following methods:

(a) By engraving, that is by providing within the setting a cavity with a lodging for the jewel and outside of said cavity on the side from which the jewel was introduced a concentric annular furrow leaving an annular ledge which could be chased over the jewel so as to fix it. The jewels called: "à glace", "à goutte" and "balancier" have for this purpose outside forms which have become classic and are very well suited for this engraving.

(b) By utilizing the elasticity of the metal of the settings and by driving the stone forcibly into a cylindrical or slightly conical hole. In this case in order to secure the fixing of the stone it was necessary to shape these stones in a very difficult and therefore expensive way and there was always a risk of waste with certain stones and the finishing work on the settings for centering the same according to the hole in the stone often caused some dislocation.

With the method of the present invention a stone is used the profile of which at the circumferential fitting surface has a convex curved form. When the stone has been introduced into the setting there is left on the ingress side of the hole an annular space which is filled up so as to prevent the stone from slipping back again.

Such a form of stone may easily be shaped and bored by special machinery with dimensions best suited for performing the process of this invention.

The jewel has usually two opposite, substantially flat surfaces or at least one such substantially flat surface and a flat outer portion on its opposite surface, and these opposite surfaces are connected by an approximately cylindrical surface. According to the present invention this circular or generally cylindrical surface is given a convex shape approximately such as would be generated by the revolution of a short arc of a circle about an axis parallel to the chord of said arc, said axis coinciding with the axis of the central perforation or recess in the jewel which is to serve as the journal bearing for a staff or shaft.

An embodiment of my invention and certain of the best methods of producing the

same are illustrated in the accompanying sheet of drawings in which:

Fig. 1 is an axial section of a jewel and a bushing therefor in position for beginning the setting process.

Fig. 2 is a similar view showing the jewel forced into the bushing.

Fig. 3 shows the finished product.

Figs. 4 and 5 are sections of modified forms of jewel prepared for use according to my invention.

Figs. 6 7 and 8 similarly illustrate a slightly modified process, and

Fig. 9 shows a further modification.

Throughout the drawings like reference characters indicate like parts. In Figs. 1, 2 and 3, a standard form of watch jewel called in French a "glace" is shown at *b*.

The whole of the convex surface of the stone is used here as fitting surface and comes therefore into contact with the metal of the setting. This surface has a circular profile. The diameter of the middle section of the stone is larger than the diameter of the two bases.

Preferably this shape of the circular surface *x* of the jewel approximates that which would be generated by the revolution of the short arc of a circle such as shown at *x* about an axis which is parallel to the chord of said arc and usually coincident with the axis of the central perforation or recess *y*, in said jewel. This surface might, however, be such as would be generated by the similar revolution of a short section of the perimeter of a polygon as shown in Fig. 4, and in Fig. 5. The curvature or taper of the jewel end so produced should be slight, so that when it is forced into a bushing of brass into which it can be wedged, a slight yielding of the metal in a direction radial of the bushing will permit the complete insertion of the jewel, and this without subjecting the jewel to a degree of pressure which would crush it. For this reason the degree of taper of the jewel surface must be slight, as shown in the drawings. The metal mass in which the jewel *b* is to be set is usually a small bushing *a* of malleable metal such as brass or copper having a central perforation, hole or recess to receive said jewel. This hole has a diameter less than the maximum diameter of the convex surface of the jewel *b* but not less than the minimum diameter thereof, so that,

when placed in the position shown in Fig. 1, the jewel fits only part way into the bushing. Fig. 2 shows the positions of the parts after such jewel has been forced down into 5 bushing, slightly expanding the surrounding bore of the bushing as indicated at *m*, until the upper surfaces of jewel and bushing are approximately in the same plane. The portion of the metal around the upper half of 10 the jewel is then forced inward against the convex jewel surface by the usual operation of a chasing tool forming a circular furrow in the bushing face as indicated at *v* in Fig. 3, or by any other suitable operation. 15 Substantially the same result may be secured if the generally convex surface of the jewel consists of a series of facets such as shown at *z* in Fig. 4, or *w* in Fig. 5, instead of being of a continuously curved or globular form. 20

In either case the finished pushed jewel presents the usual appearance of an engraved jewel setting shown in Fig. 3, but the jewel is held much more firmly in the bushing on 25 account of the "dovetailed" relation of the convex jewel periphery and the concave surrounding surface of the bushing metal which has been forced inwardly against the upper portion of said jewel surface, or forced 30 outward by pressure from the lower portion of said jewel surface.

In Figs. 6, 7 and 8 I have illustrated a modification of the process by which a modified setting is produced omitting the furrow 35 *v*. This is shown as applied to another standard form of jewel *b* called in French a "goutte". In this modification the bushing *a* is provided with a small lip *f* of V-shaped cross section extending upwardly around the 40 mouth of the bore in said bushing and above the upper surface *c*. The shapes and relative proportions of the parts are otherwise the same as before. If the forcing in of the jewel is done by a plunger of a diameter 45 large enough to overhang lip *f* it will force said lip down at the end of the plunger stroke and thus fill the space originally formed between it and the upper portion of the jewel as shown in Fig. 8, an intermediate stage of this operation being shown in 50 Fig. 7. In this process the upper face of the jewel in the finished setting may be left in a position above the plane of the upper bushing face *c'* as shown in Fig. 9, which 55 is a section of a bushing prepared for this purpose.

If it is desired to have the conventional furrow surround the jewel in a setting produced by this modification of the process, such a furrow may be initially formed about the lip *f* and will then appear in the finished setting as shown at *v'* in Fig. 9.

Of course this process could be applied to other conventional forms of jewels than 60 the two here illustrated, so long as the jewel

has one substantially plane surface extending at right angles to the axis of the central recess intended to form the journal bearing, and a circular exterior wall substantially concentric with said recess. 70

Among the advantages of the above described process may be mentioned simplicity, and ease of performance, the jewel automatically centering itself in the bore of the bushing. Also there is an automatic adjustment of final position of the jewel, in the process as illustrated in Figs. 1, 2, 3, 75 6, 7 and 8, the forcing plunger being automatically stopped at the right moment when it comes in contact with the bushing face. 80 Fracture of the jewel in the setting operation is avoided because it has a large plane surface on which the plunger bears evenly and the radial compression stresses to which the jewel is subjected are also evenly distributed. 85

The advantages possessed by the product of the process include the firmness of bond between jewel and bushing or other metal setting, accuracy of alignment between the central recess of the jewel and the bushing bore, and accuracy of relation between jewel and bushing plane faces. Also the simple form of bushing shown can be used, i. e. one without any interior ledge or other stop for fixing the position of the jewel in the bushing, or other surrounding mass of metal in which the jewel is set. 90

Having described my invention, I claim:

1. The process of setting a jewel bearing for a rotating shaft in an encircling mass of metal which comprises the following steps: shaping a circular exterior portion of a (centrally recessed) jewel to conform to a convex surface substantially such as would be generated by the revolution of a short arc of a circle about the axis of said jewel; preparing a mass of metal having a bore of a diameter less than the maximum exterior diameter of the jewel so prepared but not less than the minimum exterior diameter of said jewel; forcing said jewel into the recess in said metal mass far enough to bring adjacent flat surfaces of the two into approximately the same plane, thereby expanding a portion of said recess to the maximum exterior diameter of said jewel; and, finally, forcing the displaced metal surrounding the said expanded portion back inwardly until it closes against the adjacent convex surface of said jewel, thereby sealing the jewel in position in said metal. 105

2. A process such as defined in claim 1 in which said prepared metal mass has a short, upwardly extending lip of V-shaped cross section surrounding the mouth of said bore at the time said jewel is inserted therein. 120

3. A process such as defined in claim 1 130

in which said prepared metal mass has a short, upwardly extending lip of V-shaped cross section surrounding the mouth of said bore at the time said jewel is inserted therewith in and an annular recess in its face surrounding said lip and concentric therewith.

4. The process of forming a bushed jewel bearing for use in watches and like structures, which process comprises the following steps: shaping the circular exterior portion of a centrally perforated jewel to conform to a convex surface substantially such as would be generated by the revolution of a short arc of a circle about an axis parallel to the chord of said arc; preparing a bushing of malleable metal having a bore of a diameter less than the maximum exterior diameter of the jewel so prepared but not less than the minimum exterior diameter of said jewel; forcing said jewel into said bushing until adjacent surfaces of the two are in approximately the same plane; and, finally, forcing back against said jewel the metal of said bushing which has been

partially displaced by the above described entrance of said jewel into the bore of said bushing.

5. The product of the herein described process, being a bushed jewel bearing composed of a centrally bored jewel having the whole of its outer rim surface substantially convex, that is to say such as would be generated by the revolution of a short arc of a circle or polygon about an axis parallel to the chord of said arc and coincident with the axis of said jewel perforation, whereby either portion of said jewel rim may have a slight wedging action when forced into a bushing of originally cylindrical bore of proper diameter, and a bushing of metal having a concave inner surface conforming to and pressing against said convex jewel rim surface at substantially all points thereof.

In testimony whereof I affix my signature.

HENRI COLOMB.
